UNITED STATES PATENT OFFICE.

ROBERT S. OLIVER, OF ALBANY, NEW YORK.

DESIGN FOR AN OIL-STOVE.

SPECIFICATION forming part of Design No. 14,100, dated July 17, 1883.

Application filed April 30, 1883. Term of patent 3½ years.

To all whom it may concern:

Be it known that I, ROBERT SHAW OLIVER, a citizen of the United States, residing at Albany, in the county of Albany and State of New York, have invented and produced a new and original Design for Oil-Stoves, of which the following is a specification, reference being had therein to the accompanying drawing.

10 My invention relates to an improvement in designs for oil-stoves; and it consists in the configuration and ornamentation of the parts, as will be more fully described hereinafter, whereby a pleasing effect is produced.

15 A represents a nickel base provided with legs. The under edge of this base is scalloped in any suitable manner, so as to give it an ornamental shape. Situated above the upper side of this base is a circular plate, B, which is connected to it by the legs C, of which there are four, these legs C having fancy floral or foliate designs upon them, as shown. Within the base-ring A hangs the reservoir D. Surrounding this circular plate B is a circular 25 ring-base, E, provided with legs F, which are ornamented with suitable designs. The drum

II is cylindrical, rests upon the top of the ring-base E, and presents a smooth surface. Surrounding the drum is the top K, which consists of an inner circular collar, L, an outer 30 circumferential flange, M, and the radial arms N, which connect them, these arms having their outer ends turned down where they connect with the outer flange, so as to raise their upper surfaces some distance above the upper 35 surface of the outer circumferential flange.

I claim—

1. A design for an oil-stove, consisting of the part B, provided with the ornamental legs C, as described and shown. 40

2. In a design for oil-stoves, the door I, as shown. 45

3. A design for an oil-stove, in which the parts are arranged and ornamented in the manner shown.

In testimony whereof I affix my signature in presence of two witnesses.

ROBERT SHAW OLIVER.
